STAPLING DEVICE FOR UPHOLSTERING

Filed Dec. 11, 1947

2 Sheets-Sheet 2

the cam 13 reaches the cam roller 12 the cam 20 will engage the end 19 of the plunger 17 which will force the same in the direction of this arrow (Fig. 2) causing the end 23 of plunger 17 to engage the inner staple 40, forcing the same out, as best illustrated in Figure 2, straddling the edge wire 36, passing through the edge roll 38, engaging the forming surface 41 of the anvil 15, reversing the ends of the staple back into the roll. This completes the operation of stapling, the lever 6 is then brought to the starting position, as indicated in Figure 1, and the tool disengaged or reset along the edge roll. Figure 3 illustrates the approximate position of the staple after the operation of stapling.

It will be noted from the above description that the staple forming anvil moved towards the body of the tool previous to the outward movement of the staple through the edge roll, the object of which is to first compress the edge roll so that when the staple is driven through it will encounter a solid-like material which assists in the proper forming and clinching of the staple and also the holding and positioning of the edge roll relative to the edge wire 36. In other words the edge roll is first placed accurately relative to the edge wire then compressed and held securely in the proper position while the stapling is being performed.

I do not wish to be limited to the exact mechanical structure as other mechanical equivalents may be substituted still coming within the scope of my claims.

What I claim is:

1. A stapling tool for use in upholstery comprising a frame formed with two guide channels, a bar slidably mounted in one channel and provided at one free end with an anvil having two adjacent curved surfaces, a plunger mounted in the other of said channels and having a free end

disposed opposite the anvil, means for supplying a U-shape staple in front of the free end of the plunger, and a single operating means including a cam for first advancing the anvil toward the plunger, and a lug for subsequently advancing the plunger and staple toward the anvil to drive the free ends of the staple.

2. A stapling tool for use in upholstery comprising a frame formed with two guide channels, a bar slidably mounted in one channel and provided at one free end with an anvil having two adjacent curved surfaces, a plunger mounted in the other of said channels and having a free end disposed opposite the anvil, means for supplying a U-shape staple in front of the free end of the plunger, a single operating means for first advancing the anvil toward the plunger, and subsequently advancing the plunger and staple toward the anvil to drive the free ends of the staple, said means including a cam for moving said anvil and a lug for moving said plunger in one direction, and a spring for biasing said plunger in the opposite direction.

DINO PIERI.
